UNITED STATES PATENT OFFICE.

SAMUEL F. SWANTEES, OF ST. LOUIS, MISSOURI.

ADJUSTABLE CLOSURE FOR UNDERGARMENTS.

Application filed August 2, 1922. Serial No. 579,150.

To all whom it may concern:

Be it known that I, SAMUEL F. SWANTEES, a citizen of the United States, residing in the city of St. Louis, State of Missouri, have 5 invented new and useful Improvements in Adjustable Closures for Undergarments, of which the following is a specification, reference being had to the accompanying drawings.

10 This invention is in the way of an adjustable closure for the combined frontal and back plackets or crotch openings in the trunk of the ordinary undergarment or union suit; and the object is to provide such 15 closure in a form wherein either of the said openings may be readily elongated, at front or back, as desired, without the need of manipulating any buttons or other fastenings.

20 In the drawing:

Figure 1 is a frontal view of an undergarment constructed in accordance with this invention.

Figure 2 is a bottom plan view.

25 This invention consists in providing for the usual form of undergarment, as represented at 1, the same having combined or continuous frontal and rear plackets or openings in the trunk at the crotch, as represented at 2 and 3, respectively, an adjustable closure represented at 4, made up of two sufficiently broad bands 5 and 6 disposed diagonally and intersectingly across the said combined openings of the garment, 30 and having their respective ends suitably sewed or otherwise attached to the respective opposite sides or parts 7 and 8 of the garment at or near the said openings. The bands 5 and 6 are not secured together at

their point of intersection 9, but are here 40 left free to pass over one another. It is now obvious that by merely adjusting this point of intersection 9 forwardly or backwardly, as desired, either the rear opening 3 or the frontal opening 2 may be readily elongated 45 or extended, and this without the manipulation of any fastenings whatever. When in their normal positions, however, the bands 5 and 6 will suffice to cover the person of the wearer of the garment. 50

While I have herein described a certain specific method of constructing and assembling the elements of my invention, it is understood same may be varied in minor details, not departing from the spirit of my 55 invention as defined in the appended claim.

I claim:

In an undergarment of the ordinary construction, having combined front and back crotch openings, an adjustable closure for 60 the said openings consisting of an attachment comprising two separate bands disposed diagonally and intersectingly across the said combined openings and attached only at their ends to the garment, each of 65 said bands extending from the front of the garment to the back thereof and having both of its side edges free between its attached ends whereby the two bands are adjustable between their ends to provide an 70 elongated opening at either the front or back of the garment without manipulating any fastening device and normally substantially cover the said openings. 75

SAMUEL F. SWANTEES.
